UNITED STATES PATENT OFFICE

130,513

DESIGN FOR A METAL ROOFING SHINGLE

Rainie Bloodworth, Thomasville, Ga.

Application March 31, 1941, Serial No. 100,047

Term of patent 3½ years

To all whom it may concern:

Be it known that I, Rainie Bloodworth, a citizen of the United States, residing at Thomasville, county of Thomas, State of Georgia, have invented a new, original, and ornamental Design for a Metal Roofing Shingle, of which the following is a specification, reference being had to the accompanying drawing, forming part thereof.

The figure is a perspective view of the metal roofing shingle showing my new design.

I claim:

The ornamental design for a metal roofing shingle, as shown.

RAINIE BLOODWORTH.
